UNITED STATES PATENT OFFICE.

CHARLES F. AARON, OF NEW YORK, N. Y.

BELTING.

No. 872,882.

Specification of Letters Patent.

Patented Dec. 3, 1907.

Application filed December 18, 1906. Serial No. 348,417.

To all whom it may concern:

Be it known that I, CHARLES F. AARON, a citizen of the United States, residing at Brooklyn, city of New York, county of 5 Kings, State of New York, have invented certain new and useful Improvements in Manufacture of Belting; and I do hereby declare the following to be a full, clear, and exact description of the invention, such as will 10 enable others skilled in the art to which it appertains to make and use the same.

The invention relates to a novel method of making leather belting whereby are utilized large portions of the hide which have heretofore been unavailable for use in the better 15 grades of belting.

To this end, the invention involves the cutting of the whole hide into a strip, preferably continuous in length, the cut being 20 made substantially spiral in form, *i. e.* beginning at one end of the hide and passing by successive turns or convolutions until the final cut ends at the middle portion of the hide, straightening the strip thus cut, placing 25 several strips, cut from individual hides on edge and side by side and in close interrelation, with the weaker portion of the strips, due to the varying character of the leather in the individual hides brought in substantially 30 the same longitudinal section of the finished belting with the stronger portions of other strips, whereby the belting produced is of substantially uniform strength throughout, and finally securing the several strips together 35 by suitable transverse fastening means.

In carrying out the process, it is desirable that the hides be reduced to a uniform thickness, in order that the strips cut therefrom may be substantially uniform in cross section 40 from end to end and, incidently, the steps incident to this reduction of the hide involve the saving of valuable parts of the hide, such as the grain, which is split or skived from the upper surface of the hide in a continuous sheet, and the under portion or 45 flesh of the hide, which is likewise split off in a continuous sheet, so as to leave the middle or intermediate portion of the hide of uniform thickness throughout.

50 In the accompanying drawings, Figure 1 is a plan view of a hide, showing a preferred method of effecting the cut, for producing a continuous strip of leather. Fig. 2 is a perspective view of a small section of the hide 55 showing the mode of reducing the same to a uniform thickness and at the same time sep-

arating the more valuable grain from the upper surface and the flesh and superfluous leather from the lower surface. Fig. 3 is a longitudinal section through the hide, 60 graphically illustrating the constituent parts thereof in their relative arrangement, and the mode of separating the grain and flesh to produce the body portion, of uniform thickness, from which the strips are subsequently 65 cut. Fig. 4 is a plan view of a section of the completed belting, showing a convenient mode of securing the strips together and likewise a convenient method of securing the ends of the belting together to produce an 70 endless band or belt. Fig. 5 is a transverse section of a modified form of belting to be employed in connection with crowned pulleys.

In the general manufacture of leather 75 belting, it has been customary heretofore to take the properly tanned steer butts and cut out the only available portions for the better forms of belting, which portions are limited to the rear half of the back and the 80 flanks, leaving the neck, shoulder, and side portions as undesirable material. It will thus be seen that the available material for belting purposes constitutes somewhat less than half of the entire butt, under the conditions heretofore prevailing, and, in order to 85 produce belting of commercial lengths, *viz.* 400 to 600 feet in length, strips varying in width from a few inches to several feet and approximately 4 feet in length were cut from 90 these prime portions of the hide and united end to end by cemented lap joints, so that each hundred feet of belting would involve twenty five or more cemented joints. Under the former practice, also, when belts of 95 unusual thickness were required, it was customary to build the belting up of two or more plies, properly cemented together, the strips in the successive plies being so arranged as to break joint with each other, so that, in a two-ply belting fifty or more joints were necessary in each hundred feet and in a three-ply belting seventy-five or more joints were required. Aside from the inherent weakness of the old style of leather belting, due to its 100 numerous joints, it has been found inefficient to a degree, when applied to crowned pulleys, for the reason that the relative transverse stiffness of the belting while in operation, prevents its engaging the face of the 110 pulleys over the entire transverse surface thereof, the belting either engaging only the

- apex of the crown or the apex and one of the lateral faces, and riding out of contact with the other face, thereby reducing the efficiency of the belt as a driving medium and 5 also tending to cause the same to run off the pulleys. It will thus be seen that the former practice in the manufacture of belting was not only expensive and wasteful of the leather, but produced an article which was no 10 stronger, as a whole, than the weakest of its many joints, and moreover, could not be employed efficiently in connection with any other forms of pulleys than those having flat driving faces.
- 15 As heretofore mentioned, it is the purpose of the present invention to produce belting, in commercial lengths, and of any desired thickness, which will completely obviate the many objections to the old forms 20 of flat belting, to wit, a process which will utilize all of the material of the hides, except the irregular edges thereof, and the commercially valuable grain and flesh, which are cut therefrom, in producing belting made of 25 relatively long strips, of a width corresponding to the thickness of the finished belting, set upon edge and side by side, with the weaker portions of the individual strips arranged in the same transverse section of 30 the belting as the stronger portions of the other strips, and the whole secured together by transverse fastening means, thereby providing belting which is highly flexible in all directions, is devoid of separate plies for 35 varying thicknesses and, moreover, may be suitably hollowed or concaved on its engaging surface to accurately engage the operating surface of crowned pulleys. Moreover, belting made by this process when cut 40 in suitable lengths to form individual belts, may be accurately joined at its ends, so as to produce a perfectly smooth surface on both sides and also to introduce but a single transverse separation in the entire length of 45 the belt which is at the jointure of its ends.
- Referring to the drawings, *a* indicates a steer hide. As hereinbefore described, hides of this character afford a comparatively small amount of leather available for the 50 manufacture of flat belts, for the reason that the neck portion *b* is thick and relatively soft and porous, the shoulder portions *e* are more or less spongy and lack the tough fibrous consistency of the flank and middle 55 back portions *c* and the portions *d* are likewise not suitable for belting for the same reasons. The outer surface of the hide consists of a thin layer, commercially known as the grain, which is valuable and finds employment in many of the arts as a distinct 60 product. The grain, however, is not essential to the production of a high grade belt, in accordance with my invention, and may therefore be split or skived in a sheet of sub- 65 stantially uniform thickness from the hide.

The under surface of the hide consists of various portions of tissue and fat, known as the flesh, which, though having certain commercial value, is not desirable in the finished belting and which, therefore, may be conveniently split or skived from the hide in a continuous sheet. Generally speaking, the hide is of varying thickness, beginning at the neck *b*, which is quite heavy and spongy, it decreases in thickness until it reaches the relatively heavy fibrous portions *f* overlying the kidneys and other organs on either side of the backbone and thence diminishes in thickness toward the tail. In carrying out my process, the under or flesh portion of the hide is first skived to produce a substantially uniform surface, after which the grain is skived off, both of which operations may be effectively carried out by well known skiving. This leaves a body of uniform thickness composed of the fibrous material of the hide *a'* of the same area as the hide.

Beginning at one corner of the hide, and preferably at longitudinally opposite corners in an equal number of hides, so that alternate strips may have their initial portions taken from the shoulder and flank portions respectively of the hides, strips of uniform width are cut from the several hides, the cuts necessary to produce the strips being made in a substantially spiral form, as indicated in Fig. 1. These strips *h* are made of a width equal to the thickness of the belting to be formed therefrom, and, in order to conserve the greatest economy of material in taking the cut from a given hide, the outside cut conforms as nearly as may be to the configuration of the hide, thereby leaving but little waste material on the outside of the cut. It will be observed that each strip includes substantially every portion of a hide from the soft spongy and relatively weak neck and shoulder portions to the tough fibrous prime sections from the rear part of the back and the flanks. Nevertheless the individual strips when straightened, present a continuous length of from 400 to 600 ft., for a hide of average weight, and are uniform in cross section. Necessarily those portions of the strips which were taken from the inferior sections of the hide are weaker than the prime sections from the back and adjacent parts, so that if a single strip were alone considered, it would present an element no stronger than its weakest portion, that is to say the section taken from the porous portions of the hide. This variation in the strength and texture of the individual strips, however, is adequately compensated in the completed belting, in the following manner.

After an appropriate number of hides have been cut into strips of uniform width, the strips are placed upon edge, side by side, throughout their lengths, the butt end of one strip being so located as to lie in the same

cross section of the belting as the neck or shoulder end of some other strip, and preferably the next adjacent strip, and, correspondingly, the stronger portions of the several strips, which include the fine, tough grained portions of the hide, are brought into juxtaposition, transversely considered, with the weaker portions of other strips, so that, considered as a whole, the belting presents a structure of substantially uniform strength throughout. After the strips have been thus arranged, they are secured together by any suitable fastening means. Inasmuch as it is desirable that both faces of the belting present a substantially smooth unbroken surface to the pulleys which they engage, whether they be driving pulleys or guiding pulleys, I find it convenient to secure the several strips together by transverse devices which do not project beyond the faces of the belt. A convenient mode of securing the strips together to accomplish this purpose is shown in Fig. 3 of the drawings, and consists of a series of relatively thin flexible wire screws which are driven through the several layers or strips, transversely to the desired depth by a well known form of machine which is available for this purpose. It is not essential that the transverse screws pass entirely through the belting, but they may be arranged as indicated in staggered relation, and pass only part way through the several strips. Of course other means for securing the strips together may be employed, as for instance, fastening them by continuous transverse lacing or the like.

It is to be particularly noted that belting made in accordance with this method may be of any desired thickness, which is determined by the width of the several strips and also the length of the belting is limited only by the commercial exigencies of manipulating and storing the completed article. When it is found necessary to join two or more strips to form a continuous length, it is only necessary to square the abutting ends of the strip sections and bring them into juxtaposition between the adjacent strips. No other fastening than the devices for securing all of the strips together is necessary, as the severed ends of the strips will occupy their proper position and present no break in the continuity of the belting surface.

When it is desired to make up a belt of known length, a proper length of the belting is cut from the roll in which it is usually kept, the ends of the sections, which are to be brought together to form the joint of the belt may be conveniently fashioned in the manner shown in Fig. 4, to wit, the ends of alternate strips *h* are cut out leaving projecting tongues *j* which fit accurately into the corresponding recesses formed by cutting out the opposite strips in the other end and passing a pin or pintle transversely through the

several interlocked tongues or strip ends. While this affords a ready and convenient mode of joining the ends of the belt, it is obvious that other means may be employed without departing from the spirit of my invention.

A particular advantage inherent in a belt made in accordance with this invention is its ready adaptability to crowned pulleys, for by hollowing or concaving the lower or operating surface of the belt, as shown in Fig. 5, it may be caused to accurately engage the entire transverse surface of the crowned pulley and exercise its maximum driving effect.

To secure the best economy in carrying out the method herein proposed the grain should be removed in a thin layer from the entire hide, and when so removed may be used as a high grade leather. When the grain has been so removed and the flesh removed in the manner hereinbefore described, the entire hide, including the weaker portions and the stronger portions, should then be cut into a continuous strip and the belting built up of several strips with stronger portions of one placed adjacent to the weaker portions of the other, to obviate the defect which would otherwise exist, due to the portions of weak leather used. I appreciate, however, that such a strip may be advantageously made from less than the entire hide, for example, from a side. If only that portion of the hide is used which is commonly used for belting, that is, the rear half of the back and the flanks, no saving is attained, excepting the saving of the grain portion. If, however, any of the weaker portions of the hide are included in the strip an additional saving is at once attained, but it becomes necessary to build up the belt with the weaker portions of one strip adjacent to the stronger portions of another. Thus, if in making up a belt from strips of hide any portion of the weaker leather in the hide is so utilized the benefits of my invention are to that degree attained.

So far as I am aware, I am the first to propose in the manufacture of leather belting to remove the valuable grain in a continuous commercially salable sheet from the hide or section of hide utilized and then to cut the hide into a continuous strip, and to make up a high grade belting from several such strips placed on edge and side by side and secured together. I am also the first to propose to cut from a hide a continuous strip including the stronger and weaker portions of the hide and to overcome the weakness of these individual strips by making them up into a continuous belting by placing them on edge and side by side with the stronger portions of one strip adjacent to the weaker portions of another strip in the manner described.

What I claim is:—

1. The method of making belting which

consists in cutting a continuous strip from the weaker and stronger portions of a hide, placing several such strips on edge and side by side, so arranged that the weaker portions of the several strips lie in transverse proximity to the stronger portions of others of said strips, and finally securing the strips together.

2. The method of making belting composed of strips of leather, which consists in cutting the respective strips in continuous lengths from the weaker and stronger portions of a hide, placing the strips on edge and side by side, with the weaker portions of the several strips placed adjacent the stronger portions of the contiguous strips to produce a belting of uniform strength throughout, and finally securing the several strips together.

3. The method of making belting composed of strips of leather, which consists in cutting the respective strips in continuous lengths and of a width substantially equal to the thickness of the finished belting, from the weaker and stronger portions of a hide, placing the strips on edge and side by side, with the weaker portions of the several strips placed adjacent the stronger portions of the contiguous strips to produce a belting of uniform strength throughout, and finally securing the several strips together.

4. The method of making belting composed of strips of leather, which consists in cutting the respective strips in continuous lengths from the weaker and stronger portions of a hide, placing the strips on edge and side by side in alternate relation to cause the weaker portions of the several strips to lie adjacent the stronger portions of the contiguous strips, and finally securing the strips together by transverse fastenings.

5. The method of making belting which consists in splitting the grain from the hides in continuous sheets, cutting a continuous strip from the weaker and stronger portions of each hide, placing several such strips on edge and side by side so arranged that the weaker portions of the several strips lie in transverse proximity to the stronger portions of others of said strips, and finally securing the strips together.

6. The method of making belting which consists in splitting the grain and the flesh from the hides to reduce the latter to uniform thickness, cutting a continuous strip from the weaker and stronger portions of each hide, placing several such strips on edge and side by side so arranged that the weaker portions of the several strips lie in transverse proximity to the stronger portions of others of said strips, and finally securing the strips together.

7. The method of making belting which

consists in splitting the grain and the flesh from the hides to reduce the latter to uniform thickness, cutting a continuous strip of substantially spiral form from the weaker and stronger portions of each hide, straightening the several strips, placing them on edge and side by side with the weaker portions of the strips arranged in the same transverse portions of the belting with the stronger portions of other strips, and finally securing the strips together by transverse fastenings.

8. Leather belting composed of continuous strips of leather cut from the weaker and stronger portions of hides, the strips being arranged on edge and side by side with the weaker portions of each disposed in the same transverse section as the stronger portions of other strips, and means for securing the strips together.

9. A power belt composed of continuous strips of leather cut from the weaker and stronger portions of hides, the strips being arranged on edge and side by side with the weaker portions of each disposed in the same transverse section as the stronger portions of other strips, means for securing the several strips together, the ends of the belt being joined by alternate tongues and recesses which interlock in the respective ends and a transverse fastening device passing through the interlocked tongues.

10. A power belt composed of continuous strips of leather cut from the weaker and stronger portions of hides and of the same length, the strips being arranged on edge and side by side with the weaker portions of each disposed in the same transverse section as the stronger portions of the other strips, and means for securing the several strips together, the strips being so disposed with respect to one another that at the extremities of the belt alternate strips project beyond their fellows so that the strips form interlocking tongues and recesses, and a transverse fastening device passing through the interlocking tongues.

11. A power belt composed of continuous strips of leather cut from the weaker and stronger portions of hides, the strips being arranged on edge and side by side with the weaker portions of each disposed in the same transverse section as the stronger portions of other strips, and means for securing the strips together, the strips increasing in depth progressively from the center outward to form a lower concave surface.

In testimony whereof I affix my signature, in presence of two witnesses.

CHARLES F. AARON.
